(57) **CLAIM**

The ornamental design for a palette inner case, as shown and described.

DESCRIPTION

FIG. 1 is a perspective view of a palette inner case of the present invention in an open state.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top plan view of FIG. 1.

FIG. 7 is a bottom plan view of FIG. 1.

FIG. 8 is a perspective view of the palette inner case of the present invention in a closed state.

FIG. 9 is a front view of FIG. 8.

FIG. 10 is a rear view of FIG. 8.

FIG. 11 is a left side view of FIG. 8.

FIG. 12 is a right side view of FIG. 8.

FIG. 13 is a top plan view of FIG. 8.

FIG. 14 is a bottom plan view of FIG. 8.

FIG. 15 is another perspective view of the palette inner case of the present invention, with ink cases installed.

FIG. 16 is an exploded view showing the palette inner case of the present invention connected to an outer case; and, FIG. 17 is an exploded view showing the palette inner case of the present invention connected to a rotatable inner plate and an outer case.

The broken lines in the figures illustrate ink cases, an outer case, or rotatable inner plate and form no part of the claimed design.

1 Claim, 17 Drawing Sheets
